Specification for Design.

Patented Sept. 5, 1911.

Application filed April 17, 1911. Serial No. 621,707. Term of patent 14 years.

To all whom it may concern:

Be it known that I, GROSVENOR N. ALLEN, a citizen of the United States, residing at the city of Oneida, in the county of Madison, State of New York, have invented a new, original, and ornamental Design for Handles for Spoons, Forks, or Similar Articles, of which the following is a specification, reference being had to the accompanying drawing, forming a part thereof, in which the design consists in the form and ornamentation of the handle portion of a spoon.

The essential feature of this design consists in the marginal ornamentation of the handle of the central portion and outer end thereof as shown.

What I claim is:

The ornamental design for a handle for spoons, forks or similar articles as shown and described.
